UNITED STATES PATENT OFFICE.

BENJAMIN F. OWEN AND EDWARD L. OWEN, OF CHICAGO, ILLINOIS.

FOLDING BED.

SPECIFICATION forming part of Letters Patent No. 373,599, dated November 22, 1887.

Application filed April 28, 1887. Serial No. 236,446. (No model.)

To all whom it may concern:

Be it known that we, BENJAMIN F. OWEN and EDWARD L. OWEN, of Chicago, Illinois, have invented certain new and useful Improvements in Folding Beds, of which the following is a full, clear, and exact description, that will enable others to make and use the same, reference being had to the accompanying drawings, forming a part of this specification.

10 This invention relates to improvements in the class of upright folding beds; and the same consists of certain novel features in the construction, combination, and operation of the several parts, as will be hereinafter set forth.

15 Figure 1 is a sectional view of part of the device in the plane 1, Fig. 3, showing the bed in position for use; Fig. 2, a similar view showing the bed in the opposite or folded position; Fig. 3, a horizontal broken-away section in the plane 3, Fig. 1. Fig. 4 shows a part of the head-board and a sectional portion of the inclosing-case; and Figs. 5, 6, and 7 illustrate details of construction.

20 In the drawings, A represents the inclosing case or cabinet; B B, the side rails; B', the head-board, and B² the bed-bottom. The two levers C C are placed on each side of the bed between the bed-rails and the sides of the 25 inclosing-case, as shown in Fig. 3. The inner or bearing ends of the movement-levers are provided with the diagonal notch or recess a and the perforations a', as shown in Fig. 5.

25 a² a² are disk-plates rigidly secured to the 30 inner sides of the inclosing-case and provided with the inwardly-projecting bearing-pins a³, which engage with the perforations a'. a⁴ a⁴ are similar disk-plates (see Fig. 6) secured to the inner side of the bed rails, the pivot-pin 35 a⁵, forming an integral part of the same, passing through said rails and engaging with the diagonal notch a in the movement levers C C. The opposite ends of the levers C C are turned 40 at right angles and bolted to the ends of the transverse weight-bar D, on which are placed a number of weights, E, as shown in Fig. 3. These weights are of the form shown in Figs. 1 and 2, and are provided on the inner side with the recess b for the reception of the transverse 45 bar D, the hook part b' of the weights over-

lapping the edge of said bar in the manner illustrated in Fig. 7. By this arrangement it will be observed that the weights may be easily and conveniently removed or replaced with but little labor and trouble, and by using a 55 number of small weights instead of large ones the number may be added to or taken away from, so as to obtain the exact weight necessary to keep the bed nicely balanced in accordance with the weight of the bedding, thus 60 securing an easy movement at all times in converting the bed from one position to the other. The rectangular plates d d are rigidly secured to the back side and ends of the head-board, and are provided with the rectangular 65 notch d' for the reception of the weight-bar D, (see Fig. 7,) the projecting corners d' of the plates d d embracing the edges of the weight-bar and bearing against the same in raising or lowering the bed. By this construction 70 and arrangement the balance-weights are not attached directly to the bed proper, so that the latter may be entirely removed from the case without disturbing the weights by simply moving the head end of the bed, so as to 75 disengage the pin or pins a⁵ from the diagonal notch a in the levers C C. One end of the adjustable braces d² d² is pivoted to the inner side of the case, and may be turned upward to engage with the underside of the weight-bar 80 (see Fig. 1) to assist in supporting the same when the bed proper is entirely separated from the case. When not in use, the braces occupy the position shown in Fig. 2, the loose 85 end resting on the stop-cleats d', rigidly secured to the inner side of the inclosing-case.

The weight-bar and levers C C may be combined in a single piece, should it be an advantage to do so, instead of being in three parts, as shown.

90 Having thus described our invention, what we claim as new, and desire to secure by Letters Patent, is—

1. In a folding bed, the combination, with the inclosing-case and the folding part or section, of the transverse weight-bar, the movement-levers provided with the diagonal notch a and the perforations a', the disk-plates a², having bearing-pins a³, which engage with said perforations, the disk-plates a⁴, provided 95 with the recess b for the reception of the transverse bar D, the hook part b' of the weights over-

with pins a^5 , having a bearing in said notch, the plates d^4 , secured to the head-board and provided with the rectangular notch d' , and the projecting corners d^2 , which embrace the edges of the weight-bar, substantially as and for the purpose set forth.

2. In a folding bed, the combination, with the inclosing back case, of the movement-levers C C, the disk plate or plates a^2 , rigidly secured to the inner sides of said case and provided with bearing-pins which engage with said levers, the rails B B, the disk plate or plates a^4 , rigidly secured to the inner side of said rails and having pivot-pins which engage with the ends of said levers, whereby the folding section of the bed may be readily converted from one position to the other or conveniently detached from the back, and the

weighted transverse bar D, connecting the back ends of said levers, substantially as set forth.

3. In a folding bed, the combination, with the inclosing-case and the folding part or section, of the weighted bar D, the braces d^3 , pivoted at one end to the inner side of said case, whereby the weighted bar may be supported in place when the folding-bed section is removed, and the cleats d^4 , also secured to the inner side of said case and which provide a rest for said cleats when out of contact with the weighted bar D, substantially as set forth.
